CLAIM

The ornamental design for an extractor as shown and described.

DESCRIPTION

FIG. 1 is a perspective view of an extractor showing the new design;

FIG. 2 is another perspective view thereof;

FIG. 3 is a top plan view thereof;

FIG. 4 is a bottom plan view thereof;

FIG. 5 is a right side elevation view thereof;

FIG. 6 is a left side elevation view thereof;

FIG. 7 is a front elevation view thereof; and,

FIG. 8 is a rear elevation view thereof.

The dash-dot-dash broken lines represent bounds of the claimed design and form no part of the claimed design. All other broken lines and the unshaded areas adjacent to them illustrate features of the extractor that form no part of the claimed design.
